(57) **CLAIM**

The ornamental design for a wireless communication device, as substantially shown and described.

DESCRIPTION

FIG. 1 is a front perspective view of the wireless communication device;

FIG. 2 is a rear perspective view of the wireless communication device;

FIG. 3 is a side view of the wireless communication device; and,

FIG. 4 is a front view of the wireless communication device.

1 Claim, 4 Drawing Sheets

FIG.1

FIG.2

FIG.3

FIG.4
